UNITED STATES PATENT OFFICE

ERNEST J. BARTELL, OF CANASTOTA, NEW YORK, ASSIGNOR TO GENERAL CABLE CORPORATION, OF NEW YORK, N. Y., A CORPORATION OF NEW JERSEY

CAPSTAN

Application filed September 2, 1931. Serial No. 580,692.

This invention relates to capstans and similar winding devices such as are commonly employed in connection with wires, cables, ropes or similar material to produce longitudinal movement thereof for any purpose.

In operation, the strand of wire or other material is wound around the capstan in a spiral having a sufficient number of turns to provide the required grip. Rotation of the capstan winds the material onto one end of the spiral and unwinds it from the other end, and such operation would cause the windings to move longitudinally of the drum or capstan were some arrangement not provided for preventing such travel. Heretofore, this has frequently been accomplished by providing stationary fingers or other devices which engage one side of the material to prevent its travel along the drum and push the material back on the surface of the drum. Such devices rub or drag along the strand and sometimes cause considerable damage.

An object of this invention is to provide a capstan of the type set forth having an improved arrangement for maintaining the associated strand material in the proper position thereon.

This and other objects which will be apparent to those skilled in this particular art, are accomplished by the invention illustrated in the accompanying drawing in which

Fig. 1 is a view in elevation of a capstan constructed in accordance with one embodiment of this invention, and

Fig. 2 is a central transverse section thereof.

The particular embodiment of the invention chosen for illustration comprises a drum or capstan having a strand-engaging surface about which the associated cable or the like is wound, from three to five turns usually being sufficient to provide the necessary grip. Rotation of the capstan causes additional material to be wound on at one end of the spiral at the same time it is unwound from the other side thereof. In order to keep the turns of cable properly positioned upon the capstan without injuring the cable material in any way, the present invention contemplates the provision of a strand-guiding or

cable-shifting member associated with the surface of the capstan and adapted to move back and forth across such surface for the purpose of pushing the coils along such surface during rotation of the capstan, without causing such member to drag along the surface of the cable.

As illustrated, a drum or capstan 5 is secured to the usual supporting shaft 6 extending through a bearing block 7. The cable 8 or the like is drawn onto the capstan by rotation thereof, passed around the capstan to form a number of turns 9, and drawn off the capstan at the opposite end of the spiral. To properly position the cable and keep it properly positioned on the capstan, I provide a strand-guiding member in the form of an annular disc or ring 10 having a flange 11 extending over the strand-engaging surface of the capstan 5 and terminating in a continuous annular shoulder 12 closely adjacent the periphery of the capstan and arranged to engage the cable 8 as it is drawn onto the capstan surface. The strand-engaging shoulder 12 is caused to move back and forth across the capstan surface to push the material therealong by supporting the disc 10 for rotation about an axis at an angle to the axis of rotation of the capstan and the arrangement is such that the relative angularity of these two axes can be varied as desired. As illustrated, the disc is supported upon a ball-bearing 13, the inner stationary race 14 of which is secured in a bearing support 15, adjustably mounted on a supporting block 16 secured on the bearing 7. The roller-bearing support 15 is arranged to be adjusted about a suitable centering pin 17 by adjusting screws 18, only one of which is shown, extending through the bearing support 15 and engaging the associated supporting block 16. A flexible connection between the capstan and the disc 10 is provided for causing the latter to rotate therewith. As illustrated, this connection comprises an adjustable pin 19 supported in the capstan and extending through an associated opening 20 in the strand-guiding disc.

In operation, it will be apparent that rotation of the capstan draws the cable or similar

material onto the surface thereof at one end of the coil 9 and passes it off at the other end. The guiding disc 10 is caused to rotate with the capstan by the flexible connection, and, the axis of rotation of the disc being at an angle to the axis of rotation of the capstan, the strand-engaging shoulder 12 moves across the periphery thereof, engaging the cable and forcing the coil 9 along the capstan surface without any rubbing action between the shoulder and the cable. The angularity of the axes of rotation is such that the disc 10 is displaced from the coil 9 to provide a space into which the cable 8 can be drawn onto the drum, as will be readily understood. Suitable adjustment of the screws 18 permits any desired angular relation between the rotating parts for the accommodation of cables or strands of different diameters.

What I claim is:

1. A capstan comprising in combination a rotatable pulley and a strand-guiding member associated with the strand-engaging surface of said pulley and rotatable about an axis positioned at an angle to the axis of said pulley, and means for flexibly connecting said pulley and said guiding means for unitary movement.

2. A capstan comprising in combination a rotatable pulley and a strand-guiding member associated with the strand-engaging surface of said pulley and rotatable about an axis positioned at an angle to the axis of said pulley, means for flexibly connecting said pulley and said guiding means for unitary movement, and means for changing the degree of angularity of said axes.

3. A capstan comprising in combination a rotatable pulley and a disc associated therewith provided with a shoulder overlying the strand-engaging surface thereof, and means for operating said disc so as to cause said shoulder to move an associated strand across said surface.

4. A capstan comprising in combination a rotatable pulley, a circular disc associated therewith and adapted to engage a strand of material on said pulley, means for supporting said disc for rotation about an axis at an angle to the axis of rotation of said pulley and means for changing the degree of angularity of said axes.

5. A capstan comprising in combination a rotatable pulley, a strand-guiding member associated therewith and comprising a rotatable disc having a strand-engaging shoulder overlying the surface of said pulley, means for flexibly connecting said pulley and said disc for unitary movement, a bearing support for said disc and means for adjusting said bearing to shift the axis of rotation of said disc relatively to the axis of rotation of said pulley.

6. A capstan comprising in combination a rotatable pulley, a strand-guiding member

associated therewith and comprising a rotatable disc having a shoulder overlying the strand-engaging surface of said pulley, a flexible pin connection between said pulley and said disc, a bearing for rotatably supporting said disc, a bearing support and means for adjusting said bearing support to shift the axis of rotation of said disc with relation to the axis of rotation of said pulley.

In testimony whereof, I have signed my name to this specification this 31 day of August, 1931.

ERNEST J. BARTELL.
